UNITED STATES PATENT OFFICE.

NANDOR HONTI, OF NEW YORK, N. Y.

AMUSEMENT DEVICE.

Application filed September 10, 1925. Serial No. 55,459.

My invention relates to amusement devices and has for its object to provide a device capable of being folded in various ways to effect different combinations and more particularly contemplates the provision of a foldable picture device in which a plurality of pictorial representations are capable of being combined with each other in various combinations by predetermined folding of the device. Other more specific objects will appear from the description hereinafter and the features of novelty will be pointed out in the claims.

11, 12, 13, and 14 lie in surface engagement with the unit 10 upon the rear face thereof so that at this stage the device appears in the form illustrated in Fig. 2, the main unit 10 being exposed to view. In this condition of the device, the section 14 is located in registry with the upper portion of the main unit 10, while the units 13 and 12 are positioned in registry with intermediate portions thereof and the unit 11 is in registry with the lower portion of said main unit 10. The folded sheet thus corresponds to a single sheet having the unit 10 and the units

In the accompanying drawings, which 15 show an example of the invention without defining its limits, Fig. 1 is a face view of the amusement device in an extended condition; Fig. 2 is a face view showing the device in one of its folded conditions and Figs. 20 3, 4, 5, 6, and 7 are similar views showing additional steps in the folding of the device. 11, 12, 13, and 14 produced upon its opposite surfaces respectively. With the parts 70 in the position, illustrated in Fig. 2, the section 14 may be folded downwardly on the folding line 18, the corresponding portion of the unit 10 being coincidentally folded out 75 of sight so as to bring the unit 14 into the position indicated in Fig. 3 in which the

tation *e* with the upper portion of the pictorial representation *a* to produce the effect shown in Fig. 7. It will be obvious that any number of results, each different from the other, may be produced by means of a proper combination of main picture and secondary pictures and that all sorts of amusing or other pictorial effects may be produced.

10 The principal novelty in the present invention resides in the fact that all of the representations are produced upon the same face of the sheet of material so that the latter is capable of being easily produced by printing and is consequently adapted for production in magazines, newspapers, and the like in the form of a picture cut-out. The device requires no skill in its use and may be utilized as a medium of instruction by producing predetermined subject matter upon the sheet and the units thereof.

15 Various changes in the specific form shown and described may be made within the scope of the claims without departing from the spirit of my invention.

20 I claim:

1. A folding amusement device comprising a foldable sheet divided by parallel folding lines into a plurality of successive parallel zones, a main picture on one side of said sheet, a plurality of pictorial units within said zones, each of said units being complementary to the uncovered portion of the main picture when folded thereover, those units 25 which abut when the zones are folded over in opposed directions to completely cover the main picture being also complementary to each other.

2. A folding amusement device comprising a foldable sheet having a main picture on one side, a plurality of parallel zones on the other side foldable along the boundary lines of said zones and successively over each other and over the main picture and toward each other in each of two opposed directions, pictorial units in each zone so arranged that each zone is complementary to the uncovered part of the main picture and as it is folded over said main picture forms a different picture with the uncovered part thereof while each of those two zones which are adjacent when the main picture is wholly covered by zones folded toward each other are complementary to each other and together form a complete picture.

3. A folding amusement device comprising a sheet of foldable material, a main picture produced upon one section of said sheet, a plurality of fragmentary pictorial units produced upon the same surface of said sheet 60 upon a contiguous section thereof, the said sheet being foldable upon itself along a line between said sections to bring the main picture and the pictorial units back to back, each of said units being complementary to the uncovered portion of the main picture when folded thereover, and those two units which are adjacent to each other when the main picture is wholly covered by zones 65 folded over said main picture in opposite directions being complementary to each other.

In testimony whereof I have hereunto set my hand.

NANDOR HONTI.
